(57) **CLAIM**

The ornamental design for a cornhole bag storage utility pouch as shown and described.

DESCRIPTION

FIG. 1 is a front perspective view showing the new, original, and ornamental design of a cornhole bag storage utility pouch in a closed position;

FIG. 2 is a front elevation view of the cornhole bag storage utility pouch in a closed position;

FIG. 3 is a rear elevation view cornhole bag storage utility pouch in a closed position;

FIG. 4 is a left elevation view cornhole bag storage utility pouch in a closed position;

FIG. 5 is a right elevation view cornhole bag storage utility pouch in a closed position;

FIG. 6 is a top plan view cornhole bag storage utility pouch in a closed position;

FIG. 7 is a bottom plan view cornhole bag storage utility pouch in a closed position;

FIG. 8 is a front perspective view of the cornhole bag storage utility pouch in an open position;

FIG. 9 is a front elevation view of the cornhole bag storage utility pouch in an open position;

FIG. 10 is a rear elevation view cornhole bag storage utility pouch in an open position;

FIG. 11 is a left elevation view cornhole bag storage utility pouch in an open position;

FIG. 12 is a right elevation view cornhole bag storage utility pouch in an open position;

FIG. 13 is a bottom plan view cornhole bag storage utility pouch in an open position; and,

FIG. 14 is a top plan view cornhole bag storage utility pouch in an open position.

The broken lines in the drawings are for the purpose of illustrating portions of the article which form no part of the claimed design.
